[57] CLAIM

The ornamental design for a concrete vibrator body, as shown and described.

DESCRIPTION

FIG. 1 is a perspective view of a concrete vibrator body embodying our new design;

FIG. 2 is a front elevational view thereof;

FIG. 3 is a bottom plan view thereof;

FIG. 4 is a top plan view thereof;

FIG. 5 is a rear elevational view thereof;

FIG. 6 is a right side elevational view thereof;

FIG. 7 is a left side elevational view thereof;

FIG. 8 is a perspective view of a second embodiment, also embodying our new design;

FIG. 9 a front elevational view thereof;

FIG. 10 is a bottom plan view thereof;

FIG. 11 is a top plan view thereof;

FIG. 12 is a rear elevational view thereof;

FIG. 13 is a right side elevational view thereof;

FIG. 14 is a left side elevational view thereof;

FIG. 15 is a perspective view of a third embodiment, also embodying our new design;

FIG. 16 is a front elevational view thereof;

FIG. 17 is a bottom plan view thereof;

FIG. 18 is a top plan view thereof;

FIG. 19 is a rear elevational view thereof;

FIG. 20 is a right side elevational view thereof; and,

FIG. 21 is a left side elevational view thereof.

The broken line showings are for illustrative purposes only and forms no part of the claimed design.
